UNITED STATES PATENT OFFICE

MAURICE G. KLEMME, OF BELLEVILLE, ILLINOIS

DESIGN FOR A COOKING STOVE

Application filed August 14, 1931. Serial No. 40,849. Term of patent 3½ years.

To all whom it may concern:

Be it known that I, MAURICE G. KLEMME, a citizen of the United States, and a resident of the city of Belleville, in the county of St. Clair and State of Illinois, have invented a new, original, and ornamental Design for Cooking Stove, of which the following is a specification.

In the accompanying drawings, which form part of this specification,

Fig. 1 is a perspective view of a cooking stove embodying my invention, with the hinged top shown in closed position;

Fig. 2 is a perspective view of said stove with the hinged top thereof shown in opened position and

Fig. 3 is a perspective view of the upper portion of said stove, showing the configuration of the rear portion of the top or cover.

I claim:

The ornamental design for a cooking stove, as shown.

MAURICE G. KLEMME.
